JOHN BULLOUGH, OF ACCRINGTON, ENGLAND.

Letters Patent No. 98,919, dated January 18, 1870; patented in England, July 28, 1868.

IMPROVEMENT IN POWER-LOOMS.

The Schedule referred to in these Letters Patent and making part of the same.

To all whom it may concern:

Be it known that I, JOHN BULLOUGH, of Accrington, in the county of Lancaster, England, have invented new and useful "Improvements in Looms for Weaving," and I do hereby declare that the following is a full and exact description thereof, reference being had to the accompanying sheets of drawings, and to the figures and letters marked thereon; that is to say—

This invention consists in various improved contrivances and arrangements of mechanism, for changing, by self-acting means, the working-shuttle, in which the weft is broken or spent, for another shuttle, with fresh weft, without stopping the loom, and so on continuously, as long as the loom is at work, or until any given number of shuttles is exhausted.

The manner in which this invention is to be performed will be clearly understood by the following particular description thereof, reference being had to the figures and letters on the accompanying four sheets of drawings, in which—

Figure 1 is a front elevation;

Figures 2 and 3, end elevations; and

Figure 4, a plan of part of a loom, having my improvements attached.

Figures 5, 6, 7, 8, 9, 10, 11, 12, 13, 14, and 15, are detached views of various parts of the improvements.

Figs. 1, 2, 3, and 4, are drawn to a scale of two inches to the foot; figs. 5, 6, 7, 8, 9, 11, and 12, half size; fig. 10, full size; and figs. 13, 14, and 15, one-quarter size.

a b represent the side frames of the loom;

c, the breast-beam;

d, the crank-shaft;

e, the fast and loose pulleys;

f, the tappet-shaft;

h, the sword-arms;

i, the slay or batten;

j, the yarn-beam;

k, the treadles;

l, the healds;

m, the warp;

n, the reed;

o, the reed-cap;

p, the picking-sticks;

q r, the pickers; and

s, the stop-rod.

The weft-fork and hook *t*, the sector-hammer *u*, the horizontal weft-lever *v*, and the tappet *w*, on the tappet-shaft *f*, are the parts which constitute the ordinary weft-stopping motion in looms, and this motion I employ for calling into action the mechanism which enables the shuttles, with spent or broken weft, to be changed for fresh shuttles, with weft, without stopping the loom.

The pickers *q r* may be worked by any convenient

arrangement of under or overhead picking-sticks, but I prefer to employ the ordinary under picking-sticks *p*, connected, by straps *x*, to cams *y*, on the picking-shafts *z*, having, near their tops, catches, which, during the backward movements of the stay, turn the picking-shafts, and give motion to the picking-sticks and pickers, by coming in contact with catches, on rods which are alternately raised by the levers *a¹* and opposite tappets *b¹*, on the tappet-shaft *f*; the rods, one of which is marked *c¹*, fig. 2, falling by their own gravity when the levers are free of the tappets.

At one end of the slay *i*, figs. 1 and 2, I fix a tall back-board, *d¹*, and fix, near its end, perpendicular guides *e¹*, for forming a case or frame to receive a number of shuttles, *f¹*, full of weft, in such a manner that they have only a little play endwise and sidewise.

The shuttles are dropped into the guides *e¹*, and descend, one upon another, until the bottom shuttle rests on a ledge, *g¹*, figs. 5, 6, and 7, standing above the slay, and it is from this ledge that the shuttles are dropped, one by one, on to the slay, when there is breakage or absence of weft, the shuttle, with the spent or broken weft, being ejected into a receiving-box, *h¹*, figs. 3 and 4, at the other end of the slay.

The ends of the weft, in the shuttles in the case, are attached to a stud, *k¹*, covered with plush cloth, or other material, and fixed to the reed-cap *o*, or shuttle-case, it being necessary that the stud should be in such a position as not to leave a trail of weft to interfere with the weft-fork, and that position is either inside the weft-motion, or so high as to leave the weft at such angle from the stud to the edge of the cloth, as will clear the fork.

The ledge *g¹* forms part of a metal plate, *l*, figs. 5, 6, 7, 8, and 9, having pivots, working in bearings *m¹*, screwed to the slay-plate *n¹*, and the pivoted plate, with its ledge, is termed the shuttle-holder. When this ledge remains inward, as shown in fig. 5, it supports the pile of shuttles *f¹*, below which the working-shuttle *o¹* is free to be driven to and fro across the race of the slay. When the ledge is pulled outward, to the position seen in fig. 6, the top of the plate is moved inward, and these parts are so adjusted that before the ledge entirely leaves the bottom shuttle of the pile, the top of the plate passes under the second shuttle of the pile, and thus only one shuttle drops on the slay when the ledge is pulled entirely back. The shuttle-holder, with its ledge clear of the shuttles, and the top of the plate supporting the shuttles in the case, is retained in this position by pins *p¹* being forced by springs *q¹* into one of two recesses *r¹ s¹*, at each end of the plate, the recesses *s¹* being brought opposite the spring-pins, when the plate is brought into the position described.

When the shuttle has dropped on the slay, reverse

movement is given to the shuttle-holder, until the top of the plate moves outward, away from the edge of that which was the second shuttle, but is now the bottom one, to allow the descent of all the shuttles, and, at the same time, the ledge passes inward and supports the bottom shuttle, and, also, all the others above it, as seen in fig. 5, the recesses r^1 being brought opposite the spring-pins p^1 , when the plate is brought into the position described.

To the shuttle-holder, below the centre, I fix or cast two ears t^1 , carrying a pin, to which is attached one end of a band, u^1 , figs. 4 and 7, the other end of which is connected to a pin in the bracket v^1 , fig. 4, fixed to the horizontal weft-lever v . The band is allowed sufficient length to reach to the back centre, when the horizontal lever is not forced outward by the sector-hammer u , but when the weft is spent or broken, and the horizontal lever forced outward by the sector-hammer, the band becomes tight before the slay has arrived at the back centre, and causes the shuttle-holder to overcome the spring-pins p^1 , and swivel or turn outward on its centres, to allow a fresh shuttle to be dropped on to the slay, into the working shuttle-box w^1 , the shuttle-holder being held for an instant in this position by the ends of the spring-pins entering the recesses.

At the lower part of the plate r^1 , of the shuttle-holder, is adjusted and fixed a screw-head, x^1 , and, to a part of the frame-work, is adjusted and fixed a finger, y^1 , which, as the slay advances to the beat-up, acts on the screw-head, and causes the ledge of the holder to move inward, and the top of the plate to move outward, for enabling the shuttles to descend, and be supported on the ledge, ready for the next change, and the ends of the spring-pins p^1 spring into the recesses corresponding with this position of the holder.

The weft-fork, and parts connected with it, are placed at the same side of the loom as the shuttle-holder; and at the shuttle-box w^1 , on the slay, below the holder, I employ a front swell-guard, a^2 , figs. 1, 4, 8, and 9, to which is fastened a flat spring, b^2 , the purpose and action of which will be hereinafter described.

In order to make room for the receiving-box h^1 , which receives the ejected shuttles, the side frame, at that end, is cranked inward, and the ordinary taking-up wheels are removed to the opposite or supply-side of the loom, and, for enabling the shuttles to be ejected with facility, there is a board, inclined at an angle, downward from the edge of the slay-plate, as at c^2 , figs. 3 and 4. The front of the box may be hinged to open outward, and provided with a closing-spring, so that if a shuttle should be caught between the advancing slay and the front of the box, no damage will be done.

To prevent the picker q , at the supply-side, from rising, as it has a tendency to do, especially when the bottom ledge of the shuttle-holder is pulled outward, and to prevent its deviating from a straight line, I make, at the back of the picker, a semi-dovetail ledge, and form, at the bottom of the back-board d^1 , fig. 2, a groove, of a similar shape, to receive this ledge.

To hold back the picker q , at the supply-side of the loom, so that it cannot interfere with the dropping of the shuttles from the shuttle-holder into the shuttle-box, I employ the following contrivance: Between the inside of the shuttle-holder, and the space occupied by the stroke or traverse of the picker, I place a two-armed lever, $e^2 f^2$, figs. 4, 8, 9, and 10, on a pivot fixed to the slay-plate n^1 , and the arm f^2 , which is toward the outer end of the shuttle-box, is knuckle-jointed. The arm e^2 is turned up, and placed behind the screw-head x^1 , fixed to the shuttle-holder, so that when the holder is pulled outward, for effecting a change of shuttle, the arm e^2 is moved outward, and the arm f^2 inward, to cause its end to stand across the course of

the picker, which, generally, has not got back, after making its stroke, when the lever takes this position. The knuckle-joint yields to the backward rebound of the picker, and the moment the picker has passed the end of the arm f^2 , a spring, g^2 , closes the joint, to place the said end of the arm before the picker, and prevent it from coming forward to be in the way of the dropping shuttle. When the shuttle-holder is replaced in its ordinary working-position, the two-armed lever is moved by the screw-head, and assumes its previous position, that is, parallel to the side of the picker, but clear of it, as seen in figs. 4 and 9.

At the supply-side of the loom, I have a double lever, $h^2 j^2$, jointed to the front of the slay, in a vertical position, the top arm h^2 of which lever is in contact with a bracket, k^2 , figs. 1, 4, 8, and 9, cast to the front swell-guard a^2 , and the lower arm j^2 terminates in the form of two steps or ledges, and the lever is maintained in its quiescent position by a flat spring, p^2 . To the side frame a , I bolt an inclined bracket, n^2 , just below the stop-rod tongue o^2 , and form, on one side of the tongue, a side projection, p^2 , opposite the steps or ledges, and, at the other side, fix ears, carrying between them a bowl, q^2 , on a stud, which bowl is in line with the inclined part of the bracket n^2 .

To the side frame a , opposite the front edge of the stop-rod tongue o^2 , and above the frog r^2 , I fix a curved finger or projection, s^2 , and, at the opposite end of the stop-rod s , at the delivery-side of the loom, I fix a finger, t^2 , pointing toward the back part of the loom, which finger has, at one side, a stud, to which one end of a link, u^2 , is attached, the other end being linked to the inner end of a short lever, v^2 , figs. 1, 4, 11, and 12, fastened, at right angles, to a boss, w^2 , at the back of the back-board.

The boss is fixed, by a set-screw, to a spindle, which works in a socket, x^2 , fixed to the back-board, and has, at its front end, an arm, used as a top swell-guard.

The spindle projects through the socket to about the breadth of a shuttle, and from it branches, toward the end of the shuttle-box, the aforesaid arm, formed as a long, deep flange, y^2 , which, at the part z^2 of its top edge, is bent inward at right angles, to form a surface to act as a swell for the front top edge of the shuttle to act upon; and the spindle is held in the socket by a collar and set-screw.

When a shuttle enters the shuttle-box w^1 , figs. 5 and 6, at the supply-side, during the ordinary working of the loom, it comes in contact with the front swell a^2 , which forces the top arm h^2 of the double lever outward, and the lower arm j^2 inward, bringing the lower of the two ledges or steps, at the bottom of the lower arm, under the side projection p^2 , on the stop-rod tongue o^2 , which has been raised sufficiently high by the bowl q^2 running up the inclined bracket n^2 . The tongue, riding on this bottom ledge, is carried forward, with the slay, above the frog r^2 , but below the curved finger s^2 , placed above the frog, and no stoppage of the loom takes place.

If the shuttle is late, the ledge is not forced under the side projection p^2 , and the tongue has nothing to support it against the downward pull of the stop-rod spring b^2 , when the bowl q^2 gets sufficiently far from the back centre as to lose the support of the inclined bracket n^2 , and, therefore, the tongue is pulled against the frog, and causes the stoppage of the loom.

When the shuttle enters the shuttle-box c^3 at the other side of the loom, it glides under the top swell z^2 , and causes the boss w^2 to turn, to bring a small finger, d^2 , which passes through and is fixed to the boss in position for resisting the upward movement of the finger t^2 , on that end of the stop-rod, thus arresting the downward movement of the tongue at the other end of the stop-rod, for enabling it to clear the frog, and prevent the stoppage of the loom.

When the shuttle is late, the top swell z^2 is not

lifted by it in time to place the finger d^3 in position for resisting the upward movement of the finger t^2 , and, therefore, the stop-rod tongue is left free to be pulled down by the stop-rod spring b^3 , so that it can come in contact with the frog, and cause the stoppage of the loom.

The flanged part y^2 of the top swell acts as a guard, and prevents the shuttle from being precipitated forward off the slay, when the slay changes its direction suddenly from forward to backward; but, if this flange is raised, so as to leave the shuttle free on its front side, the shuttle will be thrown off by the forward impetus it has acquired in going from the back to the front.

I now proceed to explain how the absence or breakage of the weft causes this flange y^2 to be so raised for allowing the shuttle to be ejected.

The band u^1 , figs. 4 and 7, pulls the lower part of the shuttle-holder outward, in order to supply a fresh shuttle, when, through the absence or breakage of weft, the horizontal weft-lever v is forced outward. The shuttle-holder acts on the bracket k^2 , cast to the front swell-guard a^2 , and forces it outward, the bracket, in turn, moving the top arm h^2 of the double vertical lever so far outward, and the lower arm j^2 so far inward, as to enable the second or upper ledge formed in it to pass under the side projection p^2 of the stop-rod tongue o^2 , which has been raised sufficiently high for the purpose by the bowl q^2 , attached to it, ascending the inclined bracket n^2 . As the slay advances, the stop-rod tongue is carried, resting on this top ledge, until it comes on the lower part of the curved projection s^2 , placed above the frog r^2 ; and, as the slay continues to advance, the tongue is forced upward, causing the stop-rod itself to have more motion than it has in the ordinary working of the loom, the effect of which is to depress the finger t^2 , on the other end of the stop-rod, to such an extent as to cause the link u^2 to pull down the short lever v^2 , on the boss w^2 , and raise the top swell-guard until its flange y^2 clears the empty shuttle, which is, therefore, precipitated off the slay into the receiving-box b^1 . The arm of the short lever v^2 , figs. 1, 4, 11, and 12, which is attached to the boss, is continued past the other side of the boss, to form an arm, f^3 , which is cranked downward from a little past the boss to near the end, where it is cranked up to the original level. A common flat loom-spring, g^3 , fixed toward the end of the back-board, is made to press on this arm f^3 of the lever near the boss, the end of the arm being clear of the spring, as seen in fig. 11.

When the shuttle is entering the box c^1 , it meets with slight resistance from the top swell until it gets out of the yarn, because the spring g^3 , acting so near the boss, has not much power to cause the swell to resist the power of the shuttle to raise it, but the height the shuttle has forced the swell upward, by the time it is getting clear of the yarn, brings the end of the arm f^3 nearer to the broad and fixed end of the spring, as seen in fig. 12, thus putting more drag or check on the shuttle, and enabling the ordinary leather check-strap to be dispensed with.

For the other side of the loom, I check the shuttle on a similar principle, the mechanical arrangement being slightly varied, to adapt it to the front swell. I rivet the spring b^2 , figs. 1, 8, and 9, to the front swell-guard a^2 , the end of which spring is an eighth of an inch or so from touching the turned-up end of the arm e^2 , held by the screw-head x^1 , fixed to the shuttle-holder. The shuttle, therefore, on first entering the box, meets with very little resistance, but that resistance is increased when the spring begins to bend against the arm e^2 , and give the necessary check to the shuttle; but the parts should be so adjusted that the swell will not be forced outward so far as to bring the spring

against the arm until the shuttle has got clear, or nearly clear of the yarn.

When the shuttle, with spent or broken weft, has been ejected from the slay, the picker on that side will make a blank pick, because there will be no shuttle to throw across; and, unless there is a substitute to act on the welt-fork in the absence of the usual weft, the hook of the welt-fork will be caught by the sector-hammer, and the changing motion be repeated unnecessarily; and, to prevent this from taking place, I employ a cross-formed slide as a substitute for the weft.

To the front of the slay, I joint a two-armed lever, k^3 F , figs. 1, 13, and 14, the arm F being a little above the stop-rod tongue o^2 , and the other arm, k^3 , near the front end, m^3 , of a cross-shaped slide, n^3 o^3 , there being a part, p^3 , of the slide which projects a short distance from the back of the slay.

The slay is grooved beneath the slay-plate n^1 in the form of a cross, to receive the slide, the groove being made sufficiently wide to allow the slide to be moved to and fro in line with the slay.

When a change of shuttle is about to take place, the stop-rod tongue is carried by the upper ledge of the lower arm j^2 of the two-armed lever k^2 j^2 , fig. 2, and landed on the curved projection s^2 . The stop-rod tongue, on ascending the curved projection, acts on the bottom of the arm F , thereby causing the arm k^3 to press against the end n^3 of the cross-slide, and move it in the groove of the slay until one end of the part o^3 of the cross-slide is laid across the weft-grate q^1 , and acts on the fork as weft at the time the blank pick is given, and the cross-slide is moved back in proper time by the motion of the pick immediately succeeding the blank pick, in the following manner:

To the top of the picking-shaft z , on that side of the loom, I fix a short finger, s^3 , fig. 14, and place, on a stud in the bracket t^3 , a double lever, u^3 v^3 . The finger s^3 partakes of the motion of the picking-shaft, and acts on the double lever, forcing the arm u^3 backward, and the arm v^3 forward, against the protruding end p^3 of the slide, thereby causing the slide to move back in its groove to the position it was in before the stop-rod tongue, by ascending the inclined projection, placed one end of the part o^3 of the slide in position to act on the welt-fork as substitute weft.

As it is impossible to stop the loom, the moment the weft breaks or becomes spent, it is necessary, to avoid a thin place or crack in the cloth, to let back as much of the cloth as has wound on the cloth-beam from the time of the weft breaking to the time the loom is stopped. I may place below the ordinary ratchet-wheel a^4 , fig. 15, of the taking-up motion, a stud, b^4 , on which swivels a double lever, having one arm, c^4 , terminating in a segment, d^4 , of a ratchet-wheel, the other arm, e^4 , being weighted, so that the ratchet-end is raised in contact with the teeth of the ratchet-wheel.

When the weft-motion is brought into action, through the breakage or absence of weft, the horizontal weft-lever v , acting on the vertical finger f^4 , with which it is in contact, causes the holding-catch g^4 and the taking-up catch h^4 to be lifted, and the tension of the warp immediately sets in reverse motion the taking-up wheels, the ratchet-wheel a^4 forming one of these, and, being geared into the segmental ratchet-wheel d^4 , forces the double lever, of which it forms a part, to describe part of a revolution on its stud, which motion is only arrested by the opposite or preponderating arm e^4 of the lever being brought in contact with a stud, i^4 , fixed to the loom-side, which stud is sufficiently strong to overcome the tension of the yarn, and check the reverse motion of the wheels.

The stud i^4 , or letting-back stop, is adjustable, and may be so placed as to let back any given number of picks.

I claim—

1. The swivel shuttle-holder $g^1 l^1$, actuated one way by the horizontal weft-lever v and band a^1 , and the other way by the projecting finger y^1 , in combination with the recesses $r^1 s^1$ and spring-pins p^1 .

2. The two-armed lever $e^2 f^2$, in connection with the front swell $a^2 b^2$ and screw-head x^1 , for holding back the picker at the supply-side of the loom, when required.

3. The double lever $h^2 j^2$, with its two ledges, in combination with the incline n^2 , bowl q^2 , and curved or inclined finger s^2 .

4. The flange and top swell $y^2 z^2$, in combination with the parts $t^2, u^2, v^2, x^2, w^2, d^2, f^3$, and g^3 , for act-

ing as a swell and guard, and for allowing the escape of the shuttle when raised.

5. The cross-shaped slide o^3 , figs. 13 and 14, worked one way by the upright lever $k^3 l^3$ and stop-rod tongue, and the other way by the horizontal lever $u^3 v^3$, and also by the short finger s^3 , at the top of one of the picking-shafts, for the purpose herein specified.

Done at Manchester, England, this 30th day of April, in the year of our Lord 1869.
